UNITED STATES PATENT OFFICE

2,252,523

WINDMILL

Milton Plotkin, Chicago, Ill.

Application January 13, 1940, Serial No. 313,768

1 Claim. (Cl. 170—15)

My object generally stated is to provide improvements in windmills to the end of improving their construction and rendering them better adapted to perform the function for which they are provided.

Certain of my more specific objects are as follows:

To produce a more compact construction of windmill than hitherto provided, and one which will withstand high wind velocities;

To increase its efficiency;

To reduce the cost of such structures;

To provide a construction of windmill which will be self-starting under all conditions;

To provide against such accumulation of snow in the structure as to interfere with its proper operation;

To provide an improved shape of blade contributing to the self-starting of the windmill; and

To provide a simple, strong and sturdy construction and embodying encircling framework for the operating parts which permits of the supporting of the rotating parts in the most desirable manner.

Referring to the accompanying drawings:

Figure 1 is a view in elevation of a windmill constructed in accordance with my invention.

Figure 2 is a plan view of the structure shown in Fig. 1.

Figure 3 is a plan sectional view taken at the line 3—3 on Fig. 1 and viewed in the direction of the arrows.

Figure 4 is an enlarged broken sectional view taken at the line 4—4 on Fig. 2 and viewed in the direction of the the arrows; and

Figure 5 a fragmentary sectional view taken at the line 5—5 on Fig. 2 and viewed in the direction of the arrows.

The structure shown as to its general features of construction comprises a framework 5 in which is rotatably mounted a revoluble shield, or guard, 6 partially enclosing a blade, or wing-equipped rotor 7 exposed at one side thereof to the force of the wind; the shield 6 being provided with fins 8 and 9 which cooperate to ensure the proper automatic positioning of the shield, relative to the direction of the wind, regardless of its direction.

The framework 5 as shown comprises an annular series of uprights 10 shown as equidistantly spaced apart and six in number and which in the case of the smaller sizes of windmills may be, by way of example, of angle form as shown, and in the case of the larger sizes of windmills of

fabricated form, these uprights being connected at their upper ends to a rigid ring 11 shown as seated on the upper ends of the uprights 10; with the frame-bar 12 extending centrally across the ring 11 and secured thereto.

The structure thus produced is shown as braced by wire stays 13 connected at their upper ends with the ring 11 and the ends of the frame-bar 12 and anchored at their lower ends in the ground.

The frame-bar 12 affords an upper bearing 14 for a shaft 15 forming a part of the rotor 7 and by which the power generated by the windmill is transmitted to any device to be driven thereby, as for example an electric generator.

A lower bearing 16 beneath the shield 6 is provided for the shaft 15, this bearing being rigidly connected with the upper ends of radiating inclined bars 17 the lower ends of which are connected with the lower ends of the uprights 10, forming a sturdy bearing structure.

The shield 6 as shown is formed of an upper series of spokes 18 radiating from a hub 19 journaled on the shaft 15, and connected at their outer ends with a ring 20, and a lower series of spokes 21 radiating from a hub 22 journaled on the shaft 15 and connected at their outer ends with a ring 23, the rings 20 and 23 being connected together at intervals by vertical rods 24, the spokes 18 and 21 thus forming an openwork rigid structure.

The lower hub 22 rotates on the bearing 16 between which parts a ball-bearing 25 is preferably interposed to reduce friction in the rotation of the shield 6.

The shield 6 also comprises a vertical arcuate side wall 26 rigidly secured at its upper and lower edges to the rings 20 and 23, and by preference being of a circumferential length slightly less than 180° to present a vertical leading edge 27 and a vertical trailing edge 28.

The shield 6 carries the two radially disposed fins or blades 8 and 9 which extend the full height of the shield and are rigidly connected at vertical edges with certain of the rods 24 and at their upper and lower edges to extensions of certain of the spokes 18 and 21, the extensions of the spokes 18 being shown at 18a. The fins 8 and 9 are spaced apart, preferably about 90°, about the circumference of the shield and at equal distances from a diametrical line passing through the leading edge 27 and the axis about which the shield rotates. The fin 8 is located at the side-wall-equipped portion of the shield and extends radially outwardly therefrom and is preferably

set back a slight distance from the trailing edge 28 of this wall, as for example a distance substantially equal to the width of the fin as shown; and the fin 9 is located at the open side of the shield with its inner edge terminating in substantially the cylindrical plane occupied by the wall 26 as shown.

The rotor 7 comprises an upper and a lower series 29 and 30, respectively, of arms, each series being shown as comprising six arms but the number of which may be varied, the upper arms being directly above the lower arms, and the series of arms being connected at their outer ends with the apex portions of upper and lower hexagonal frames 31 and 32.

The lower arms 30 are connected, respectively, at their inner ends to a ring 33 surrounding, and secured to, the shaft 15 and supported on a ball bearing 34 interposed between this ring and the lower bearing 22 of the shield. The upper arms 29 are connected at their inner ends to a ring 35, surrounding, and secured to, the shaft 15.

The blades or vanes of the rotor 7 are represented at 36 being shown as of general rectangular shape, radiating from the shaft 15 to which, and to the arms 29 and 30, they are secured. In the particular construction shown six of the blades equidistantly spaced apart are provided. However, their number may be varied as desired.

The blades 36 extend at their outer vertical edges a slight distance short of the arcuate wall 26 and project outwardly through the open side of the shield 6 as they progressively move beyond the leading edge 27 of the wall 26.

The structure also, by preference, comprises plate-like cover sections 37 and 38, the upper one 37 being shown as of hexagonal shape and carried by the rotor 7 and the lower one 38 of circular shape and carried by the shield 6, certain of the purposes of which are to reduce the likelihood of snow accumulating in the operating parts and impairing the proper functioning thereof, and to confine the air impacting the blades at the open side of the shield.

In the operation of the windmill the leading edge 27 of the shield 6 is held into the wind, at all times and despite change in direction of the wind, by the action of the wind against the fins 8 and 9. Possibility of the stalling of the shield in a position in which the portion thereof diametrically opposed to the leading edge 27 faces the wind, is prevented by reason of the pocketing of the wind in the interior angle 39 between the fin 8 and the trailing edge portion of the wall 26 which exerts a turning movement in excess of that exerted against the fin 9, rotating the shield 6 into a position in which the wind automatically rotates the shield into alignment at its leading edge 27 with the direction in which the wind is blowing.

The wind striking the blades 36 at the open side of the shield 6 beyond its leading edge 27 operates to rotate the rotor 7 and with it the

shaft 15, the wind, as the blades progressively move beyond the diametrical center line of the structure at the open rear side of the shield, escaping freely, and therefore avoiding the building up of pocketed, or back, pressure which would present resistance to the rotation of the rotor.

To avoid failure of starting and to produce the maximum power output, the blades 36 are provided of the form shown, namely, the forward or outward vertical edge 40 of each blade is of greater length than its rear or inner edge and the blade is curved or bowed as represented in the direction of its length, the blade progressively decreasing in curvature lengthwise of the blade from its outer edge toward its inner edge which is straight in the lengthwise direction.

By providing the blades 36 of this form the force of the wind striking them exerts a greater impetus for driving the rotor 7 in the desired direction than in the opposite direction ensuring the starting of the rotor regardless of the particular position assumed by the rotor when at rest. Furthermore, the provision of the blades as stated minimizes the tendency to produce back pressure and undesirable eddies against the oncoming blade as it passes beyond the leading edge 27 of the shield in the continuing rotation of the rotor.

As will be understood, the provision of the fins 8 and 9 as described which may be made of relatively narrow width, renders the structure comprising the moving parts, very compact permitting such structure to be housed within a framing of relatively small dimensions with the advantage of the provision of vertically spaced bearings for the rotating parts, making for compactness and relatively inexpensive construction while providing for the firm holding of the operating parts against lateral deflection.

While I have illustrated and described a particular construction embodying my invention I do not wish to be understood as intending to limit it thereto as the same may be variously modified and altered and the invention embodied in other forms of structure without departing from the spirit of my invention.

What I claim as new and desire to secure by Letters Patent, is:

A windmill comprising a support, a blade-equipped rotor on said support, a shield for said rotor on said support, said rotor and shield being independently rotatable, said shield having a side wall extending part way only around said shield and presenting a leading edge, and spaced apart fins on said shield at its rear side disposed at opposite sides of a diametrical line passing through said leading edge and the axis about which said shield rotates, one of said fins being located at said side wall and set in from the trailing edge of said wall to form, with said wall, a pocket, and the other of said fins being remote from said side wall.

MILTON PLOTKIN.
